UNITED STATES PATENT OFFICE.

OLIVE E. FRANK, OF BUFFALO, NEW YORK, AND HERBERT P. WILDER, OF DETROIT, MICHIGAN.

WATER-HEATING SYSTEM.

Application filed July 23, 1926. Serial No. 124,398.

This invention relates to water heating systems for use in connection with domestic storage tanks and wherein the water may be heated by the furnace or by a gas burner or 5 by both.

The object of the invention is to provide a combination heater element which is adapted, without valve complications, for use either interchangeably or simultaneously 10 with the furnace or with a gas burner and by means of which the piping is materially simplified and reduced in cost. With the above object in view the invention consists generally in the combination of a shell divided into 15 compartments each having a heating coil, and heads connected at the adjacent inlets and the adjacent outlet ends of both coils and piped to the storage tank.

An embodiment of the invention is illustrated in the accompanying drawings wherein:

Figure 1 is an elevation of the complete system.

Figure 2 is a front elevation of the water 25 heater.

Figure 3 is a plan view of the water heater.

Figure 4 is a detailed sectional view on the line 4—4 of Figure 2.

30 In Figure 1 the furnace is shown at F, the storage tank at B and the water heater at H. The heater consists of a shell 1 having a separable front wall 2, preferably formed in sections and secured to the shell by bolted flange

35 connections 3. The shell has a central vertical partition 4 by which it is divided into two compartments 5 and 6. The compartment 5 encloses a coil 7 and the compartment 6 encloses a coil 8. The coil 7 is used when

40 the water is heated by the furnace and the coil 8 is used when the water is heated by the gas burner 9 which is arranged in the lower part of the compartment 6. The furnace includes a water or steam back (not shown)

45 which is connected to the compartment 5 by pipes 10 and 11 whereby the heating medium, hot water or steam as the case may be, flows through the pipe 10 and compartment 5 and returns to the furnace by the pipe 11, the 50 water in the coil 7 being heated by the medium flowing through the compartment 5.

The storage tank B is connected to the coils 7 and 8 by pipes 12 and 13. Communication between these pipes and the coils is provided 55 for by heads 14 and 15 respectively which

are suitably secured to the sections of the front wall, the terminals of the coils being continued through the front wall as shown in Figure 4 in the case of the head 15, and having water tight connection with the front 60 wall. The coils 7 and 8 are thus both always filled with water from the storage tank B.

In the winter time when the furnace F is in daily use the water in the storage tank B is heated by the furnace, the coil 7 being utilized. In the summer time when the furnace is not in use the water in the storage tank B is heated by the gas burner 9, the coil 8 being utilized. During the use of the furnace there will be times when the quantity of hot water 70 required will be in excess of that which has been or may be provided by the coil 7 and at such times the gas burner may be lighted so as to bring the coil 8 into operation, the two coils then being used simultaneously until 75 the amount of water desired has been heated at which time the use of the gas burner may be discontinued. The products of combustion of the gas burner may be carried off by a pipe 16 communicating with the top of the 80 compartment 6 and access to the gas burner for any purpose desired may be had by a normally closed door 17 provided at the rear of the compartment 6. If desired the water heater may be employed in connection with 85 any suitable temperature control applicable to the gas burner side. Such controls being well known the illustration of the same is unnecessary.

Having fully described our invention, we 90 claim:

1. In a water heating system the combination with a furnace and a storage tank, of a shell divided into laterally adjacent compartments, a water heating coil in each compartment, a separably secured cover plate for each compartment and to which the terminals of the coil in said compartment are connected, fluid conducting pipes connecting the furnace and one compartment, a burner 95 for heating the water in the coil in the other compartment, chambers with which the adjacent terminals of the coils communicate and water conducting pipes extending between said chambers and the storage tank. 100

2. In a water heating system a water heater comprising a shell having a central partition by which it is divided into compartments and having a separably secured front wall, a heating coil in each compartment, 110

casings carried by said front wall and providing chambers with which the adjacent terminals of said coils communicate, in combination with a storage tank, a furnace, 5 water conducting pipes extending between said chambers and the storage tank, water conducting pipes extending between one com-

partment and the furnace and a burner for heating the water in the coil in the other compartment.

10

In testimony whereof we affix our signatures.

OLIVE E. FRANK.
HERBERT P. WILDER.
